UNITED STATES PATENT OFFICE.

ABRAHAM HORROCKS, OF BARDOLPH, ILLINOIS.

BRICK AND TILE MACHINE.

SPECIFICATION forming part of Letters Patent No. 295,871, dated March 25, 1884.

Application filed April 23, 1883. (No model.)

To all whom it may concern:

Be it known that I, ABRAHAM HORROCKS, of Bardolph, in the county of McDonough and State of Illinois, have invented new and useful Improvements in Brick and Tile Machines; and I do hereby declare that the following is a full, clear, and exact description of the same, reference being had to the accompanying drawing, which forms part of this specification.

This invention relates to that class of brick and tile machines where the clay is tempered and forced out through the dies by means of augers; and its novelty consists, first, in a vertical chamber, in which is placed a vertical pugging or mixing and forcing screw, said vertical chamber joining a horizontal chamber, in which is placed a horizontal mixing and forcing screw, which extends entirely across the lower end of the vertical chamber, and is enlarged at the inner end under the vertical pugging-screw, so as to fill the space between the bottom of the horizontal chamber and the lower end of the vertical pugging-screw, whereby the clay, while passing through the machine, is thoroughly mixed and forced through the dies without liability of packing or clogging in the machine.

My invention consists, further, in facing the blades or flanges of the pugging or mixing screw with steel plates, which enables them to withstand a greater amount of wear with a less amount of friction, as will be hereinafter more fully set forth.

In the drawing, which represents a vertical sectional view, A is a vertical chamber, which is joined to or made part of the horizontal chamber B, both of which are mounted on a suitable frame or bed.

In suitable bearings in the chamber A is placed the pugging or mixing and forcing screw, which is made of cast or wrought-iron, either a continuous screw, or made in section and secured to the shaft d in any suitable manner.

B is a horizontal pugging or mixing and forcing screw, placed in suitable bearings in the horizontal chamber. This screw is made

tapering, the enlarged end being placed under the lower end of the vertical pugging-screw, so as to fill the contour of the horizontal chamber, the blades of the screw being made a sufficient size to fill the space between the bottom of the horizontal chamber and the lower end of the vertical screw in the vertical chamber. This is an important feature of my invention, as the clay, which is fed in at the upper end of the vertical chamber, is kept in a continuous motion in its passage through the machine, is thoroughly and intermediately mixed in all its parts, and all packing or clogging of the clay in the chambers, both vertical and horizontal, is entirely obviated.

c are the screw blades or flanges.

s s represent steel plates, which are bolted or riveted to the screw-blades *c* on the working or the side which receives the pressure. These steel plates cause the screw to wear much longer, and by use receive a high polish, which greatly reduces the friction of the screw while pressing the clay through the machine, the advantages of which are obvious.

The operation is as follows: Motion is imparted to both screw-shafts in any convenient manner, and the clay is fed in at the top of the vertical chamber A, and by means of the blades of the screw the clay is forced down onto the horizontal screw B, which forces the clay forward and out through suitable dies secured to the outer end of the horizontal chamber. (Dies not shown.) By this combination and arrangement the clay is kept in a constant motion from the time it enters the machine until it is forced out in the proper shape for brick or tile.

Having thus described my invention, what I claim as new, and desire to secure by Letters Patent, is—

1. In a brick or tile machine, a vertical chamber having therein a vertical pugging or mixing and forcing screw, said vertical chamber being joined and forming a part of a horizontal chamber, in which is placed a horizontal mixing and forcing screw, said screw being tapering and adapted to fill the space

between the lower portion of the horizontal chamber and the lower end of the vertical screw, as set forth.

2. The combination of the vertical screw with a tapering horizontal screw extending entirely across the horizontal chamber, as shown and described.

3. The combination, in a brick or tile ma-

chine, of the screw flanges or blades *c* with the steel plates *s s*, secured to their working-faces, substantially as shown and described, for the purpose set forth.

A. HORROCKS.
